PACKAGING ARTICLE

Clarence W. Vogt, Norwalk, Conn.

Application April 15, 1949, Serial No. 87,638

2 Claims. (Cl. 229—55)

1

This invention relates to improvements in receptacles for packaging various solid and liquid commodities, and in particular to a flexible-walled container which may be protectively retained in or provided with added stability by a rigid or semi-rigid support structure.

This application is a continuation-in-part of my copending applications Serial No. 30,647 filed June 2, 1948, and entitled Method of and Article for Packaging Materials, now Patent No. 2,628,013; Serial No. 38,477 filed July 13, 1948, and entitled Bag Assemblies; Serial No. 79,591 filed March 4, 1949, and entitled Receptacle; Serial No. 41,384 filed July 29, 1948, and entitled Apparatus for and Process of Manufacturing Enwraps, now Patent No. 2,626,544; Serial No. 64,666 filed December 10, 1948, and entitled Apparatus for and Method of Combining Enwraps; and Serial No. 49,277 filed September 14, 1948, and entitled Apparatus for and Method of Combining Enwraps.

It is an object of the present invention to provide a package which may be adapted to contain fluent materials, such as liquids, which may be constructed so that the contents of the package are visible to provide an attractive display package. At the same time the packaging of fluent materials requires greater strength, resistance to rough handling and leakproofness than packages for other materials.

Another object is to provide a composite receptacle including a flexible-walled enwrapment protectively retained by a rigid or semi-rigid frame construction which is designed so that it may be fabricated as a composite blank and adapted to be erected or assembled at the time that it is used for packaging. In the handling and distribution of many commodities the storage of containers prior to packaging creates a substantial problem. For example, in the dairy industry the use of glass containers or semi-rigid sheet material containers which may be impregnated with wax, requires a large amount of storage and handling space. This is particularly true in connection with glass bottles which are normally intended for return and reuse and must therefore be handled to clean and prepare them for reuse. The handling and reuse problem makes it advantageous to utilize wax coated paper or cardboard milk bottles which are intended to be disposable after use. The economics of this problem places a burden on a relatively small packager who finds it difficult to remain competitive due to the investment required in real estate, buildings and equipment necessary for such storage. By the

present invention, containers prior to use may be stored in flattened condition, and therefore, relatively large numbers of them will occupy only a small space.

5 A further object of the present invention is to provide a receptacle which is designed to make it inexpensive from the standpoint of cost of materials as well as mode of use. Where a completed package can be produced at a decreased cost it is obviously uneconomical to provide for return and reuse of the receptacles.

Another object is to provide a receptacle for fluent materials having an opening means for gaining access to the contents which is leakproof, 15 easy to open and may be reclosed to prevent contamination of the remaining contents.

A further object is to provide an opening for such a receptacle which is designed and positioned to facilitate flowing or pouring the contents from the receptacle.

20 Another object is to provide a package utilizing a flexible walled enwrapment which may be advantageously used for the packaging of food products and the like since the package may provide the characteristics of being non-toxic, odorless, tasteless, capable of being sterilized, etc.

A still further object is to provide a package adapted to be fabricated in a flattened form for erection or assembly at the time the contents are placed therein and which may be connected to 30 one or more similar articles to facilitate their handling and use as pairs, or as a series, or as a series of pairs. In this way advantage may be taken of multi-unit fabricating and packaging apparatus to produce a greater number of filled packages without requiring a large amount of additional apparatus.

35 Another object is to provide a package including a flexible walled tubular enwrapment adapted to be filled and protectively retained in a semi-rigid sheet material frame in which placement of the contents into the package is greatly facilitated since it may be accomplished through an open end of the tubular enwrapment.

40 Other objects and advantages will become apparent from the following detailed description accompanied by the drawings in which:

45 Figure 1 is a plan view of a section of sheet material which has been fabricated into a connected pair of blanks suitable for forming a semi-rigid frame;

50 Fig. 2 is a similar plan view showing a plurality of connected pairs of blanks to which the tubular enwraps have been assembled;

Fig. 10 is an enlarged elevational view of the connected pair of articles as shown in Fig. 9 but taken at right angles to Fig. 9;

Fig. 11 is a perspective view of a completed package embodying the present invention;

Fig. 12 is a sectional view taken substantially in the direction indicated by the dot and dash line marked 12—12 in Fig. 11;

Fig. 13 is an enlarged fragmentary perspective view of a completed package to illustrate how the same may be opened to gain access to the contents;

Fig. 14 is a fragmentary perspective view of a portion of the bottom of a completed package to illustrate an added feature of the package construction; and

Fig. 15 is a sectional view similar to Fig. 5 but illustrating a modified form of the invention.

Briefly, a preferred embodiment of the present invention comprises a package including a flexible walled tubular enwrapping which may be sealed so as to render it liquid tight and may be protectively retained by a frame or supporting structure of suitable sheet material, preferably of a semi-rigid or rigid nature. The completed package is preferably provided with means for obtaining ready access to the contents, which may also afford a pouring spout to facilitate emptying the contents when they are of a fluent nature. The composite package may be fabricated in a flattened or knocked-down condition and may thus be readily stored and shipped compactly until desired for use. In its fabricated condition it may be termed a blank and is adapted to be filled manually or by any suitable mechanism which will at the same time place the package in its erect or assembled position.

The knocked-down packages or blanks lend themselves to being handled during fabrication thereof and during packaging therein, in pairs, or in a series, or in a series of pairs. This feature permits greater production of completed packages in a given time unit without an undue increase in the amount of apparatus required.

It is believed that the design and construction of a finished package may best be understood by a description of the fabrication, filling and sealing of a preferred form of package embodying the present invention. Figs. 1 through 10 illustrate the principal operations in obtaining a completed package.

In Fig. 1 a section of sheet material is disclosed and defined or incorporated in the sheet material are the necessary component parts of a pair of

outer protective frames or supporting structures for a pair of flexible walled enwraps. Such frames are preferably of the type disclosed and claimed in my above referred to copending application Serial No. 79,591 filed March 4, 1949. Each of the frames or support structures in its flattened condition comprises a central panel 1 which in set up or assembled form may provide a side panel of the completed package. Extending outwardly from opposite side edges of the panel 1 but integrally joined therewith are panels 2 and 3 which in assembled condition may form top and bottom panels respectively for the completed package. Extending outwardly from the panel 3 but integrally connected thereto along a common edge, a retaining flange or panel 4 may be provided. The panel 4 in assembled condition becomes a partial side wall for the completed package extending in substantially parallel relation with the side wall formed by the panel 1.

Each of the panels 1, 2, 3, and 4 may be provided with integral but outwardly extending flange portions 5, 6, 7, and 8 respectively which in assembled position constitute partial edge walls for the completed package. In addition these flange portions may be disposed in overlapping relationship and connected together to secure the supporting structure in its assembled position. For this purpose the flanges at desired positions may be provided with adhesively coated areas indicated by the numeral 9 to provide a secure adherence between overlapped portions of these flange portions. As may best be seen in Fig. 11 the flanges 8 on the top panel 2 overlap with and may be secured to end portions of the flanges 5 on the side panel 1. Similarly the flange portion 8 on the front panel 4 and a portion of the flange portion 5 of the side panel 1 may overlap with the flange 7 on the bottom panel 3 and with each other to secure these portions of the frame together and provide a rigid end portion for the frame. If desired the panels and flange portions may be defined along their common boundaries by score or fold lines 10. Further, the adjacent flange portions along each side of the flattened frame may be separated by edge slits 11.

As stated, it is believed advantageous to fabricate and handle a plurality of packages or their component parts while they are connected together and thus in Figure 1, a readily separable form of connection has been disclosed. Such connection comprises a central slit portion 12 with a pair of outwardly disposed integral lands or connecting portions 13 and if desired, edge slits 14 may be provided along the common boundary between the pair of adjacent frames. With this type of separable connection the flattened frames may be fabricated in precise and accurate registry with their common boundary accurately defined. However, due to the integral connecting portions 13 they may be treated simultaneously throughout the making and filling of the finished packages. At the same time, when it is desired to separate them into individual units the connection is such that this may be readily accomplished. The complete severance may be done by a mechanism (not shown) utilizing an unsharpened central portion adapted to act as a finder or locator and be inserted through the central slit 12. Outwardly from the central or finding portion the mechanism may be provided with opposite and angularly disposed cutting edges which act to sever the integral connecting portions 13. With such an arrangement the final severance may be made and the forces required to

effect severance will be disposed in opposite directions extending along the common boundary acting to counterbalance each other. There will be little, if any, force exerted tending to disturb the balance of the sheet material sections.

The next operation in the manufacture of the blank is the assembly with the flattened supporting frame, of a tubular enwrapping and since as illustrated in the drawings, the frames are to be handled in connected pairs, the tubular enwrappings may also be disposed in pairs. The lower portion of Fig. 2 illustrates a double length of integrally connected tubular sheet material which has been superposed with a pair of flattened frame members. This tubular material 15 may be formed of any suitable flexible sheet material and may be severed to provide a pair of tubular enwrappings 15. Since the supporting structure in assembled position is provided with cut-out face portions which give a view of the 20 enwrappings, it is believed preferable to utilize a transparent or translucent material so that the contents of the package will be displayed. Further, it is especially advantageous in the packaging of food products, chemicals and liquids where 25 high purity is essential, that the sheet material from which the flexible walled tubular enwrapping is made be relatively or substantially inert so that it will not affect or be affected by the contents.

In the case of food products, the sheet material should preferably be non-toxic, odorless and tasteless, and capable of withstanding sterilizing temperatures. Where the package is to be exposed to the weather or other extreme conditions it should in addition, be able to withstand a relatively wide range of temperature variation, sunlight, moisture, fumes, etc., which might deteriorate the package or adversely affect its contents. Examples of sheet materials which will 35 withstand a number of these conditions are polyethylene, polyvinylidene chloride, vinyl resins, rubber hydrochlorides, cellulose derivatives, etc. It is also desirable that the film or sheet material be of a heat sealable nature to facilitate the making of a secure closure for the enwrapping. The 40 selection of the particular film or sheet material will be dependent upon the commodity or objects to be packaged, and in addition, to the conditions which such package may encounter.

Either prior to or after assembly of the pair of tubular enwrappings 15 with the pair of flattened frames, there may be secured to the tubular enwrappings one or more sections of suitable strip material. Fig. 2 illustrates the superposition of elongated strips of sheet material or tapes 45 16 to the marginal end portions of the pair of tubular enwrappings. Also, the numeral 17 indicates a further elongated strip or tape of sheet material which is disposed with its center line coinciding with the common boundary between the tubular enwrappings 15. The tapes 16 and 50 17 may be continuously or partially adhesively coated with a suitable adhesive material to adhere them to the paired tubular enwrappings 15. For example, Fig. 2 illustrates the tape 16 as being provided with an adhesive area 18, of a suitable adhesive substance, of an extent such that the tape 16 completely adheres to the marginal portion of each of the tubular enwrappings to which it may be superposed. Similarly the tape 17 may be provided with an adhesive area 19 which is also of an extent sufficient to adhere to the entire width of the tubular enwrapping 15. However, as will be seen later it is believed preferable to 55

activate only that portion of the adhesive area 19 which overlies the top panel 2 so that the portions of the tape which overlie the side flanges 6 are not adhered to the tubular enwrapping (see Fig. 5).

As the double length of tubular enwrappings 15 are placed in superposition on the pair of flattened frames, the frames may have previously been provided with adhesive areas indicated by the numerals 20 and 21 respectively to adhere end portions of the tubular enwrappings to the flattened frames. The drawings indicate that the adhesive areas 20 and 21 are preferably of a different type of adhesive than the adhesive areas indicated by the numerals 9. For example, it is considered advantageous to adhere the tubular enwrappings to the flattened frames by an adhesive which may be of a solvent or emulsion type, or a pressure sensitive adhesive substance. In some instances the thermoplastic adhesive as indicated by the areas 9 may be suitable for adhering together the sheet material from which the flattened frames may be made, whereas such adhesive may not provide sufficient bond to adequately secure the tubular enwrappings to the flattened frames.

As shown in the upper portion of Fig. 2 the central tape 17 and the tubular enwrappings 15 have been covered along the common boundary between the tubular enwrappings 15, without however completing the severance of the pair of flattened frames disposed therebeneath. While the drawings illustrate diagrammatically the assembly of a connected pair of tubular enwrappings with a connected pair of flattened frame members, it will be obvious that the same result may be obtained by assembling two individual tubular enwrappings to the connected pair of flattened frames in which case the central tape 17 will be a pair of independent tapes rather than a severed central tape. It is considered beneficial as will be later described to dispose the central tape 17 so that an edge thereof is precisely flush with the marginal edge of the tubular enwrapping and this result can best be achieved by applying a double width tape and severing the tape and tubing simultaneously.

When the flattened frames, tubular enwrappings, and tapes have been assembled and adhered together it may be seen that the pairs of assembled blanks are connected as a series of pairs and may thereafter be advanced as a series by applying force to leading ones of the series. In this position the ends of the tubular enwrapping which overlie the bottom panels 3 and are adhered to the end tapes 16, may be sealed to effect a closure of the tubular enwrapping. Several of the sheet materials from which the tubular enwrappings may be formed are heat sealable materials but which have the property upon being heated to the region of their sealing temperature, of shrinking to an objectionable degree. For this reason the presence of the adhesively coated tapes 16 is beneficial. It has been found that the presence of a tacky substance in contact with at least one of two surfaces to be heat sealed has the effect of preventing the objectionable high shrinkage of such surfaces. This phenomenon is more thoroughly described in my copending application Serial No. 53,333 filed October 7, 1948. While the advancing of the assemblies by the tapes 16 and 17 may have a tendency to distort the tubular enwrappings with respect to the flattened frame members, if there is a resistance to the advanc-

ing of the frame members, the sealing of the free ends of the tubular enwrapping will prevent further action of this type. It may be desirable to support the flattened frames on driven rollers or conveyors or to advance the assemblies by driven belts prior to sealing of the ends of the tubular enwrapping to prevent dislocation of the tubular enwrappings with respect to the frames. After the sealing of the tubular end portions through the tapes 16, it is believed only necessary to support the flattened frame members on a stationary surface along which they may slide. The commodity being packaged may make it desirable to support the blanks during filling, sealing, etc., on a movable conveyor or the like.

To obtain access to the contents of a filled and completed package, and particularly where the package contains liquid or flowable materials, it is believed preferable to provide an opening which may also constitute a pouring spout. The drawings illustrate such an opening which may be provided during the assembly and fabrication of the package and in the present instance such opening is positioned at a point differing from the location at which the tubular enwrappings are filled. Such an opening may comprise a tongue formed in the frame or support structure and liftable therefrom. This tongue may be disposed at a location where the flexible-walled tubular enwrapping is adhered to the frame or support structure. Also, at a desired location beneath the tongue the flexible-walled tubular enwrapping may be severed or cut-scored or weakened in any suitable way so that when the tongue is lifted the connection of the tubular enwrapping and the tongue will cause the enwrapping to be lifted with the tongue starting from the location of the severance or weakening. In Figure 1 it may be noted that the top panels 2 of the flattened frame members are provided with cut-score lines 22 which define the side portions of a liftable tongue indicated by the numeral 23 and best seen in Figs. 11 and 13. Extending onto the side panel 1 and connecting the ends of the cut-score lines 22 which define portions of the tongue is a severance line 24. It may be noted that the severance line 24 outlines a free end portion of the tongue 23 which diverges as it extends away from the top panel 2. At the time that the tongue 23 is defined in the flattened frame member it is preferable to bend outwardly a free edge portion of the tongue as indicated by the numeral 26. Deformation of the free end portion 26 will permit access to the tongue for the purpose of opening the package since such free end portion will not be adhered to the tubular enwrapping, although the enwrapping and frame may be secured together throughout the remaining region of the tongue member.

Beneath the tongue 23 and preferably in the region of the boundary between the top panel 2 and the side panel 1, the flexible walled tubular enwrapping is provided with a cut line 25 which preferably extends transversely of the tongue and beyond the side edges of the tongue. The cut line may be of any suitable design either arcuate or straight according to the character of the opening and/or pouring spout which it is desired to provide. For purposes of illustration it has been shown as a straight line extending along the common boundary between the top panel 2 and the side panel 1 which in the completed package will be a corner edge.

With the tubular enwrapping being adhered to the frame throughout the general region of the tongue, it is believed advisable to form the cut line 25 after assembly and connection of the tubular enwrapping and frame. In this way there will be no opportunity for separation of the marginal edges of the enwrapping adjacent the cut line which might tend to permit leakage of the contents prior to opening of the package. Figs. 6 and 7 illustrate diagrammatically one method by which the cut line 25 may be formed after assembly of the tubular enwrappings and frames. The numeral 27 illustrates a support member over which the series of pairs of uncompleted packages may be advanced. At the desired location, raising the bisected central tape 17 will effect an opening of the tubular enwrapping sufficient to permit the insertion of a die member indicated by the numeral 28. Mounted in the die member 28 is a pair of cutter elements 29 which are of the desired configuration to provide the cut line 25. The die member 28 is moved with respect to the support 27 a sufficient distance and with sufficient pressure to cut completely through the wall of the tubular enwrapping but does not cut through the frame member to which the enwrapping is adhered.

After the opening means for the finished package has been made the series of pairs of receptacles may be advanced to filling position where the commodity to be packaged may be placed therein. As the tubular enwrappings approach filling position the bisected portions of the tape 17 may be spread outwardly and since the opposed wall portions of each tubular enwrapping are held together by being secured to the connected pair of flattened frame members the mouths of the tubular enwrapping will be opened and permit insertion of a suitable filling spout or nozzle (not shown). During filling each pair of blanks may be suitably supported at the desired angle which may be varied in accordance with the nature of the material to be placed in the tubular enwrappings.

Fig. 8 illustrates a filling position in which the blanks are supported from a support 30 so that they depend in substantially vertical position. If desired the support 30 may have angularly inclined surfaces 31 to support the bottom panels 3 of the frame members and the bottom sealed portion of the tubular enwrappings at an angle. It is believed that this will facilitate the filling out of the bottom portion of the tubular enwrapping and may lessen the stress to be placed upon the bottom sealed portions of the tubular enwrappings. Obviously other angular positions of the opposite members of the pairs of blanks may be utilized. When the proper amount of the contents of the tubular enwrappings have been placed therein, the bisected portions of the central tape 17 may be utilized to close the mouth portions of the tubular enwrapping. As described in connection with the sealing of the bottom portion of the enwrapping the thermoplastic adhesive coating 19 on the bisected tape 17 may be utilized to hold the wall portions of the tubular enwrapping against shrinkage while autogeneously welding together the marginal portions of the filled tubular enwrapping. Figs. 9 and 10 illustrate a position at which the marginal edge portions of the tubular enwrapping may be moved together for sealing. The sealing may be accomplished by any suitable

heating elements such as plates or rollers (not shown).

After filling and sealing, the package may be completed by suitably folding and forming the various panels and flange portions of the frame member to their assembled position. It is believed that any sequence of folds which will produce a neat appearing package will be satisfactory and the folds illustrated in the drawings merely show one way of accomplishing this. The side flanges 5, 6, 7, and 8 may be formed so that they are substantially perpendicular with the panels 1, 2, 3, and 4 respectively. Next the bottom panel 3 is formed to a position substantially perpendicular with the side panel 1, with the flanges 7 of the bottom panel underlapped with respect to the flanges 5 of the side panel. Next, the front panel 4 is formed to a position of 90° with respect to the bottom panel 3 and the flange portions 8 of the front panel 4 are overlapped with respect to the flange portions 7 of the bottom panel 3. If of sufficient extent these flange portions 8 may be underlapped with respect to the flange portions 5 of the side panel 1. The adhesive areas 9 on the flange portions may be activated to tacky condition so that the flange portions will securely adhere together and provide a rigid or semi-rigid support structure or frame.

At the top end of the container the flange portions 6 of the top panel 2 may be formed at right angles to the top panel 2 and as the top panel 2 is formed at right angles to the side panel 1 the flange portions 6 are overlapped with the flange portions 5 of the side panel 1. Adhesive areas 9 on the flange portions 6 may be activated to securely bond the flange portions 6 and 5 together, forming a top end wall for the package. Figs. 11 and 12 illustrate two views of the filled, completed package.

At the time the frame members are to be formed or assembled to their erect position it may be desired to sever the connected pairs of blanks so that each package may be set up as a unit. Alternatively the bottom portions of the packages may be assembled to erect form prior to the severance of the pairs. It may also be desirable to remove each of the pairs from the series of packages and this may be done by severing the tapes 16 and 17 which have been utilized to chain the pairs into a series, at the two opposite side edges of each pair of blanks. This will leave sections of the tape adhering to the tubular enwrapment at the sealed ends thereof and such tape may act as a reinforcement for the sealed end portions. Further, if the activation temperature of the thermoplastic adhesive areas 18 and 19 are below the activation temperature of the heat sealable tubular enwrapment, the adhesive areas 18 and 19 may be activated and the tapes removed without affecting the sealed end portions of the tubular enwrapment.

Fig. 13 illustrates the opening of the package to gain access to the contents thereof. Such opening may be readily accomplished by lifting the tongue 23 by means of the free edge portion 26 and peeling the end portion of the tongue from the flexible walled tubular enwrapment until the cut line 25 in such wall is reached. At this point the wall of the tubular enwrapment is completely severed transversely across the tongue 23 and further lifting of the tongue will tear the flexible wall of the enwrapment along the lines 22 which define the tongue. By tilting

the package about an axis spaced from the corner edge between the top panel 2 and the side panel 1, the contents if fluid may be poured over the remaining edge of the flexible enwrapment wall 5 at a spout portion indicated by the numeral 32 on Fig. 13. To effect a reclosure of the opening the free end of the tongue may be pressed downwardly to wedge the tongue between the side edges of the frame along the cut score lines 22 from which the tongue was lifted. The flared free end portion of the tongue will assist in creating this wedging action and will serve to satisfactorily maintain reclosure of the opening.

Where the finished product is adapted to contain liquids it may be desirable to provide means for including a tube or straw with the package to permit drinking the contents through the opening. One method of accomplishing this is to provide a flap or tongue 33 at any desired place, through which the tube or straw may be inserted and removed. In Figure 1 the flap or tongue 33 is shown as being struck at a corner of the bottom panel 3 adjacent the front panel or retaining flange 4. Then, as illustrated in Figs. 11 and 14, a tube or straw 34 may be inserted on the interior of the frame or supporting structure between the frame and the flexible walled tubular enwrapment. This position of the straw is advantageous since it extends diagonally of the package and may be of sufficient length to reach the bottom of the contents during use. The flap or tongue 33 may be disposed in other locations but it is believed desirable that it be at the bottom of the package since any condensation forming on the open face of the tubular enwrapment and flowing into the bottom portion of the frame may drain through the opening afforded by the flap or tongue 33.

Fig. 15 illustrates a modified form of blank for forming a receptacle similar to that described in Figs. 1 through 14. Fig. 15 differs from the previously described form of the invention in that the tubular enwrapment 15' comprises a tube having infolds or gussets indicated by the numeral 41. It is believed that this form of the invention is advantageous since during fabrication and filling of the enwrapment it is superposed only above the central, top and bottom panels, and does not extend transversely outwardly to overlie the flange portions.

It may be noted that completed packages made in accordance with the present invention provide a useful and attractive display package, which is particularly adapted for packaging of liquids or fluent materials. The combination of a tubular enwrapment and a semi-rigid support structure will provide excellent strength characteristics and high resistance to blows or shocks due to rough handling or dropping. It will be obvious that the flexible enwrapment will result in greater strength than a container merely having wall portions of fibrous material such as paperboard, whether or not the same be coated with a plastic substance or wax, as coatings do not increase the wall strength of the container.

In connection with the packaging of liquids where an especially secure liquid-tight seal for the tubular enwrapment is desired, it may be desirable to permit the sections of strip material or tapes 16 and 17 to remain on the end seals of the enwrapment for reinforcement purposes. When the tubular enwrapment is provided with tucks or gussets as indicated in the form of the invention shown in Fig. 15, the tapes 16 and 17 and also beneficial since they assist in sup-

11

porting the tucks or gussets during handling, closing, and sealing of the enwrapment. However, it will be understood that in some instances, and particularly where the tubular enwrapment is made of a high-strength material it may be desirable to remove the tapes after they have served their purpose. Where the adhesive coating on the tapes comprises a thermoplastic or other reactivatable adhesive substance, this may be readily done by activating the adhesive and peeling or removing the strip or tape. The tape may be peeled as soon as the sealing of the enwrapment walls has been accomplished if the adhesive on the tape retains its tackiness for sufficient time to permit the seal of the enwrapment to cool or set to a point where its strength is high enough to withstand peeling.

It is contemplated that in some cases it will be desirable to provide the tapes 16 and 17 with adhesive areas 18 and 19 respectively which may be of more than a single adhesive. In this way each adhesive may be present to serve a particular function. For example, in a case where polyethylene is used to form the tubular enwrapment it is known that many adhesives do not adhere to this material with a satisfactory bond. Accordingly, the tapes may be provided with adhesive areas of a suitable thermoplastic material such as tape manufactured by Nashua Gummed & Coated Paper Company and sold under the trade-marks "Pervenac" and "I-Mac." In addition these tapes may have a coating of an adhesive such as that sold by Dewey and Almy Chemical Company under the trade-mark "Darex." This latter adhesive may be applied in liquid form and will provide a secure bond for advancing the blanks by the tapes during their use in packaging and for opening the mouth end of the tubular enwraps to permit fabricating operations or filling of the blanks. The adhesives on the "Pervenac" and "I-Mac" tapes are thermoplastic and provide an excellent tacky surface to hold the wall of the tubular enwrapment against shrinkage during sealing. Also, since the adhesive on these tapes has a lower activation temperature than that of polyethylene it may be activated to remove the tapes after sealing of the polyethylene. It must be recognized that the selection of the proper adhesive or adhesives may vary according to the properties of the materials of which the package is made, the commodity to be packaged, and the use to which the package must be subjected.

Similarly, it may be desirable to utilize different materials for making the support structure or frame and this factor may also affect the selection of the proper adhesives. In the packaging of liquids a suitable fibrous material having the desired strength and rigidity may be utilized and in addition it may be provided with a suitable coating such as a wax-like substance or other moisture repellent coating. Such a coating may facilitate retaining a liquid-tight closure in the region of the opening covered by the tongue 23. For example, at the time the severance or weakened line 25 is formed, heat may be applied to the frame in the region of the tongue 23. If the sheet material has a wax coating on one or both of its surfaces, the heat will soften the wax and it may flow and set to seal the severance line 25 as well as the overlying edge portions of the tongue 23 along the cut-score lines 22.

While the drawings illustrate the wall of the flexible enwrapment as provided with an actual severance line 25 it will be understood that this

12

weakened portion may be provided in other ways, so that as the tongue 23 is lifted a portion of the wall of the enwrapment will be raised by its adherence to the tongue commencing with such weakened portion. The weakening of the enwrapment wall may be accomplished by stapling or stitching the enwrapment wall to the tongue 23 at the desired location and in this case it may not be necessary to bond the enwrapment wall to the tongue.

Blanks made in accordance with the present invention are believed to be especially advantageous for a number of features which facilitate their use in packaging and the provision of an inexpensive but extremely useful package. In the making and assembling of the tubular enwrapment and support structure it will be noted that the enwrapment may be properly located with respect to the blank, filled and sealed, and then the support structure may be assembled or erected around the package. The tubular enwrapment must be positioned with respect to the support structure so that each wall thereof will extend for approximately half the perimeter of the completed package. Alternatively, the package may be formed by filling and sealing the tubular enwrapment and assembling it with a flattened or assembled supporting frame. Inspection of the filled packages is simplified as defects may be observed prior to erection of or assembly with the frame member.

Also, the tubular enwrapment 15 may be more readily filled due to the fact that the filling opening may be as much as desired, limited only by the diameter of the tube. As shown in the drawings the tubular enwrapment may be readily opened since the adhesive area 20 which holds one of the walls of the enwrapment to the frame may extend to the edge of the mouth of the enwrapment. The opposite wall may be opened due to the adhesively coated tape which is adhered thereto. When the enwrapment is to be filled with liquids, the tape may be used to open the mouth sufficiently to permit entry of a nozzle or spout, and filling may be accomplished without foaming or contamination since the enwrapment is collapsed or flattened and there is no requirement to displace air present in the container. The filled contents act to expand or distend the enwrapment. Where this factor is particularly desirable the nozzle may be designed so that it will form an air-tight seal at the mouth of the enwrapment.

It will also be noted that the frame or support structure contributes to the desirable features of the package. It may be made relatively inexpensively since it may be designed as a rectangular section of sheet material, obviating the need for expensive dieing out operations and creating savings in materials due to its lack of outwardly extending tabs or wings. Further, while it is of sufficient extent to adequately protect the enwrapment, the material required to form it is considerably less than that required to form a conventional carton or box.

The frame or support structure may be readily formed or erected to complete the package and may be held in erected form by the adherence of the overlapped flange portions. It is also contemplated that if desired, these flange portions may be partially overlapped and erected prior to assembly with the tubular enwrapment. The partial assembly of the support structure is considered beneficial since it will establish the desired sequence of folds and will partially form

such folds at the proper locations. As described in my copending application Serial No. 79,591 filed March 4, 1949, the partially assembled support structures or pairs of support structures may be readily produced in large quantities and nested to compact condition for storage or shipment to the place where they are used for packaging. After being assembled with a tubular enwrapment and the contents placed in the completed blank, the completion of the assembly or erection may be carried out by simplified mechanism. This feature is illustrated in Figs. 8 through 10 which show the partial assembly of the bottom panel 3, the front panel 4 and their side flanges 7 and 8. Where the tubular enwrapment is in the form of a flat tube without gussets, the sealing of the top portions of the filled enwrapment may be simplified if this portion of the support structure is not partially assembled. Where the enwrapment is gusseted it is feasible to partially assemble all of the panel and flange portions of the support structure.

In conjunction with the sealing of the mouth portion of the tubular enwrapment it is possible to simultaneously date or code the packages as is generally done in the packaging of some foods and other high purity products. Either the tape or the support frame may be provided with the desired coding information so that each package may be identified.

Packaging costs may also be substantially decreased by the present invention since the blanks are adapted to be connected in pairs, or in series, or in a series of pairs and thus multiple filling of a plurality of packages may be accomplished. This appreciably increases the output of the packaging apparatus without unduly increasing the cost of such apparatus. It may also substantially decrease the amount of labor required per package unit.

Since the components of the receptacles described and illustrated are relatively thin sheet materials and involve the use of adhesives, the drawings have in many cases been exaggerated and distorted to facilitate illustration of the details of the construction and the operations involved in packaging. Further, while for purposes of clarity certain portions of the package have been denoted by the terms "bottom," "side," and "top" it will be obvious that the completed package may be supported in any desired position. However, since the completed package has been designed to provide an improved display package,

it is believed generally preferable to utilize it in the position shown in Figs. 11 and 12 of the drawings.

It will be understood that the foregoing description of preferred embodiments of the invention is for the purpose of explanation and illustration and numerous variations and modifications other than those which have been described may be made without departing from the spirit of the invention.

What I claim is:

1. As an article of manufacture, a pair of frame members of semi-rigid sheet material, means connecting the frame members along a common edge of the members, a pair of flexible bags each having a closed and an open end, means to secure the closed ends of the bags to the frame members adjacent the outer ends thereof, and means to secure a side of each bag adjacent to its open end to each of the frame members adjacent the common edge thereof, said last named securing means extending over a portion less than one-half the perimeters of the open ends of the bags adjacent the open ends thereof, and means secured to an opposite side of each bag from the frame and adjacent to its open end to apply tension for opening each bag.
2. The article set forth in claim 1, wherein the frame members are connected together along a portion only of the common edges thereof.

CLARENCE W. VOGT.
